(57) **CLAIM**

The ornamental design for a 30 amp right angle locking electrical head with handle, as shown and described.

DESCRIPTION

FIG. 1 is a front elevation view of a 30 amp right angle locking electrical head with handle, showing our new design;

FIG. 2 is a rear elevation view thereof;

FIG. 3 is a right side elevation view thereof;

FIG. 4 is a left side elevation view thereof;

FIG. 5 is a bottom, front and left side perspective view thereof;

FIG. 6 is a top plan view thereof;

FIG. 7 is a bottom plan view thereof; and,

FIG. 8 is a bottom, rear and right side perspective view thereof.

The broken line in the figure drawings is included for the purpose of illustrating unclaimed environment and forms no part of the claimed design.
